UNITED STATES PATENT OFFICE.

CHARLES F. TAYLOR, OF NEW YORK, N. Y., ASSIGNOR OF ONE-HALF TO ADOLF BANGERTER, OF NEW YORK, N. Y.

RADIATOR FILLER-CAP.

1,359,471.

Specification of Letters Patent. Patented Nov. 16, 1920.

Application filed August 9, 1919. Serial No. 316,292.

To all whom it may concern:

Be it known that I, CHARLES F. TAYLOR, a citizen of the United States, and a resident of the city of New York, borough of 5 Manhattan, in the county and State of New York, have invented a new and Improved Radiator Filler-Cap, of which the following is a full, clear, and exact description.

This invention relates to safety appliances for caps or receptacles and has particular reference to filler caps for automobile radiators.

Among the objects of the invention is to so connect a cap to the filler neck as to provide for the quickest and easiest possible 15 means for opening the neck for introducing water to the radiator.

Another object of the invention is to provide a means to make a permanent connection 20 between the cap and radiator structure whereby any possibility of loss of the cap by carelessness or by theft will be prevented.

With the foregoing and other objects in 25 view the invention consists in the arrangement and combination of parts hereinafter described and claimed, and while the invention is not restricted to the exact details of construction disclosed or suggested 30 herein, still for the purpose of illustrating a practical embodiment thereof reference is had to the accompanying drawings, in which like reference characters designate the same parts in the several views, and in 35 which—

Figure 1 is a front perspective view of a portion of a radiator showing my improvement attached thereto.

Fig. 2 is a vertical sectional view of the 40 cap and neck on the line 2—2 of Fig. 3.

Fig. 3 is a vertical transverse section on the line 3—3 of Fig. 2.

Fig. 4 is a horizontal sectional detail on the line 4—4 of Fig. 2, the plane of the section coinciding with the plane of the contact between the lower edge of the cap and the upper edge of the neck; and

Fig. 5 is a sectional detail on the same plane as Fig. 2, but with the cap swung 50 open.

Fig. 6 is an enlarged sectional detail view.

Referring now more specifically to the drawings I show a radiator 10 to which is

attached a neck 11 of any suitable form in 55 cross section, but having a permanent connection with the main portion of the radiator. The upper edge of the neck 11 is smooth and lies in a horizontal plane, but being preferably beveled as shown. 60

The cap 12 comprises a top 13 and a downwardly projecting flange 14. The top 13 may be of any suitable form or design according to the desire of the designer of the car so that the identity of the car being 65 established more or less by the appearance of the radiator cap, the cap need not be disturbed, although obviously any design of cap may be adopted in the spirit of this invention. The flange portion 14, however, 70 should preferably be designed to constitute a virtual continuation of the neck 11, it being preferably for this purpose of the same size and form as the neck and is provided with a smooth lower edge which lies directly upon the smooth upper edge of the neck when the cap is closed, and a beveled shoulder between which and the beveled surface of the neck 11 there will be sufficient 75 space or clearance to permit a limited movement of the cap with respect to the neck. Any suitable means may be provided to connect the cap to the neck so as to swing the cap from its normal closed position around a vertical axis arranged at one side 80 of the center of the neck so as to hold the cap in open position and yet maintain its connection permanently with the neck. 85

The means I prefer to effect the connection between the cap and the neck includes a 90 pivot lug 15 fixed to or formed as an integral part of the upper portion of the neck at one side thereof, the upper surface of the lug except as soon to be noted lying flush with the plane of contact between the cap 95 and the neck. This upper surface of the lug, however, is provided with a notch 15' extending preferably along the top of the lug in a radial direction with respect to the radiator neck. The notch, however, does 100 not extend across the adjacent wall of the neck. In other words the upper edge of the neck is continuous at the point 15' as well as elsewhere for two reasons soon to be made apparent. First, the continuity of 105 the neck rim being unbroken, the appearance of the neck and cap structure is practically the same as the ordinary screw cap

structure; secondly the wall at 15^a serves to assist in holding the cap in true centered position.

The means employed to hold the cap to the neck and normally in closed position includes a pivot pin 16 extending upward through a hole 17 in the lug 15 and parallel to the axis of the neck, one end of the pin passing upward through a lug 18 fastened to or formed integral with the cap. The lugs 15 and 18 in plan are preferably the same form so that normally the latter registers directly above the former. Obviously the hole 19 formed in the lug 18 and through which the pin projects must always register with the hole 17. Any suitable means may be provided to lock the pin in place, as for instance a head on one end and bent over points at the other. The points indicated at 20 are shown as lying in a notch 21 formed in the upper end or surface of the lug 18 and at any desired distance below the top 13 of the cap.

The lower surface of the lug 18 is provided with a projection 22 formed as a counterpart of the notch 15', or substantially so. The outer end of the projection 22 bears normally against the inner surface of the wall section 15^a while the lower surface or point of the projection extends downward into the notch under the force of an expansion spring 23 located between the head of the pin and the bottom surface of the lug 15.

To open the cap the operator simply pushes it around the axis of the pivot pin 16 to the position shown in Figs. 2 and 4 in dotted lines, and in Fig. 5 in full lines. This movement of the cap to open position 40 is resisted only by the expansive force of the spring tending to hold the projection 22 in the notch 15' and the outer end of the projection snugly against the inner surface of the rim section 15^a. This function of 45 the spring prevents any accidental displacement of the cap from normal position and therefore the joint between the cap and the neck will be maintained substantially tight

and prevent splashing of the water there-through as well as to preserve the neat appearance of the structure. The cap may be 50 swung around its pivot either by grasping it directly by the hand or by pushing it by any other device if it is too hot to grasp with the hand. The cap may be swung 55 freely in either direction and from any position to any other position, except as moderately resisted by the force of the spring as described above. When the cap is swung around its axis the projection 22 riding up 60 either side of the V-notch, by cam action, causes the lifting of the cap automatically and hence requires no thought or effort on the part of the operator to lift the cap so as to cause it to clear the parts normally holding 65 it from rotation.

I claim:

In a device of the character set forth, the combination of a neck having a smooth upper edge lying in a horizontal plane and 70 a concentric beveled surface, a lug extending inward from the upper edge of the neck and flush therewith, but provided with a notch extending radially toward the center of the neck, the wall of the neck, however, 75 at the outer edge of the notch being continuous or unbroken, a cap having a downwardly projecting flange and beveled shoulder meeting the upper edge of the neck there being a limited movement between the said 80 shoulder and beveled surface, a lug carried by the cap and having a projection extending downward normally below the meeting plane of the cap and neck and constituting a counterpart of said notch, the outer end 85 of the projection abutting normally against the section of the wall of the neck at the outer end of the notch, a pivot pin passing through the lugs parallel to but at one side of the axis of the neck, and an expansion 90 spring between one end of the pin and the adjacent lug, tending to hold the projection seated in the notch and the outer end of the projection against the abutting wall as aforesaid.

CHARLES F. TAYLOR.
